Primary Examiner — Cynthia Underwood*(74) Attorney, Agent, or Firm* — Gardere Wynne Sewell LLP; Andre M. Szuwalski; John Jacob May(57) **CLAIM**

The ornamental design for a simulated bolted hardware, as shown and described.

DESCRIPTION

FIG. 1 is a perspective view of a simulated bolted hardware; FIG. 2 is a top plan view of the simulated bolted hardware; FIG. 3 is a bottom plan view of the simulated bolted hardware;

FIG. 4 a front elevation view of the simulated bolted hardware, the rear elevation view is a mirror image thereof; and,

FIG. 5 is a right side elevation view of the simulated bolted hardware, the left side elevation view is a mirror image thereof.

The broken lines in FIGS. 1 and 2 form no part of the claimed design.
